UNITED STATES PATENT OFFICE.

LESLIE R. McDONALD, OF WESTMOUNT, QUEBEC, CANADA.

SELECTIVE INFORMATION APPARATUS.

Application filed March 4, 1922. Serial No. 541,161.

To all whom it may concern:

Be it known that I, LESLIE R. McDONALD, a citizen of the United States, residing at Westmount, Province of Quebec, Dominion 5 of Canada, have invented certain new and useful improvements in Selective Information Apparatus, of which the following is a specification.

My invention relates to that class of information apparatus wherein a guide index is associated with a plurality of placards, each of which may be selectively and mechanically separated from the others and exposed to view, and subsequently returned to 15 its normal position; and my improvements are directed particularly to means for increasing the scope and efficiency of the guide index in its cooperation with the placard selecting and exposing mechanism; and also 20 to means for simplifying the selecting and exposing mechanism, and making it positive, accurate and efficient in operation.

The particulars of my improvements I will now proceed to point out and explain, 25 referring, in so doing, to the accompanying drawings, in all of which the same parts are designated by corresponding reference numerals, and in which Fig. 1 is a front elevation of my improved apparatus; Fig. 2 is a 30 vertical sectional view, taken as on the line 2—2 of Fig. 1, looking to the right, many of the elements being omitted, as the figure is intended primarily to show the general 35 arrangement of the mechanism; Fig. 3 is a front view, on an enlarged scale, with the exterior casing removed, and with part of the mechanism on the left side omitted for clearness, vertical and cross sections being 40 omitted to condense the figure; Fig. 4 is a side view, taken as looking from the left on Fig. 3, but omitting certain parts for clearness; Fig. 5 is a top view of the forward 45 part of the mechanism, the casing being removed, and the figure being condensed by the omission of medial portions; Fig. 6 is a vertical sectional view of the operating handle with its locking mechanism in neutral 50 position; Fig. 7 is a similar view showing the locking plunger depressed; Fig. 8 is a detail on an enlarged scale of the placard gripping mechanism; Fig. 9 is a detail of 55 part of the leaf turning mechanism, showing it in a slightly different position from that in Fig. 5.

The mechanism of the apparatus is 55 enclosed within a casing 1, which is provided

with an open or transparent front portion 2, behind which the guide index or a selected placard may be exhibited.

The flat, table-like portion 3 of the case is, 60 preferably, closed, except that it carries a pair of guides 4, 4 between which is a slot 5, through which travels the operating handle 6, which is provided with a plunger 7, normally raised, as in Fig. 1, by a coiled 65 spring 8, and which, when depressed, operates on the pivoted latch 9 to throw its lower end outward, as shown in Fig. 7.

Plates 10 and 11 are connected by studs 12, 13, the plate 10 being attached to the 70 upper portion of the handle 6, and the plate 11 carrying its lower end 14.

A pair of rails 17, 17, mounted in the casing, form a track for a traveling frame, having toothed side racks 18, 18, connected 75 by suitable cross bars 19, 20, the under sides of the racks 18, 18 being provided with V shaped grooves 21, 21, to accommodate the ball bearings, 22, 22, so that the travel of 80 the balls relative to the racks 18, 18 shall be less than their travel on the rails 17, 17, and in the normal shifting of the frame its center of gravity will not pass beyond the support of the balls.

Flattened rods 25, 25, the ends of which 85 rest across the notches 26, 26 of the racks 18, 18, carry the placards 27, 27, the ends of the rods 25, 25 extending beyond the outer sides of the racks, as shown.

To the cross bar 19 is pivoted a latch 30, 90 held to duty by a spring 34, and a rack bar 31, which are connected by a rod 32, attached to the rack bar by one end and having its other end traveling in a slot 33 in the latch 30, so that the latch and bar may move 95 freely toward each other, but may not separate further than permitted by the rod 32.

To the frame of the apparatus is attached another rack bar 35, into engagement with 100 which the bar 31 may be moved, thereby locking the traveling frame against movement.

On a pair of slides 36, 36, attached to the frame of the apparatus, travels the cross head 37, carrying the pulleys, 38, 39, 40, and 105 being pivotally connected by its arms 41, 42, with the pistons 43, 44 of the dash pot cylinders 45, 46, pivoted at 47, 48 to the frame and connected, for the purpose of equalizing the pressure, by a tube 49, the air in 110 which may be controlled by a plug 50.

To the cross head 37 is also pivoted a

latch 55, having a spring 56 bearing against its heel, and holding it normally in the position shown in Fig. 5.

Pulleys 51, 52 are mounted in the frame 5 of the apparatus; and pulleys, 57, 58 are mounted on slotted carriers 59, 60, held adjustably in the frame of the apparatus by the set screws 61, 62.

Also, to the frame of the apparatus is 10 pivoted a latch 65, to which is connected one end of a rod 66, the other end of which is bent so as normally to engage behind the cross head 37. A coiled spring is stretched between the latch 65 and the frame of the 15 apparatus. It is omitted in Fig. 3, for clearness. On a pair of uprights 70, 70 are mounted pulleys 71, 72, 73, 74, and through vertical slots in the uprights slide the ends 20 of a cross bar 75, provided with guide blocks 76, 76, to each of which is pivoted an arm 77, one end of which projects through the slot and is provided with a cross pin 78 adapted to cooperate with a pair of cams 79, on the inner face of the upright. The 25 arms 77 are, preferably, recessed on their under sides, as shown in Fig. 8, and, from each of the guide blocks 76, a guttered arm 80 projects through the slot in its upright 70.

A cord or cable 84 is attached at one 30 end to one of the arms 77, from which the other end is led up over the pulley 72, down to pulley 71, and then in succession around pulleys 57, 38, 51, 39, 52, 40, 58, 73 and 74, and is then attached to the opposite 35 arm 77, so that the weight of the guide blocks 76, 76 and cross bar 75 is carried, through the arms 77, 77, by the cable 84.

Three index leaves 90, 91, 92 are carried 40 by bars, 93, 94, 95 pivotally mounted in the frame of the apparatus; and are respectively provided with crank arms 96, 97, 98, the arm 97 being slotted to receive a pin 99 in the end of an arm 100 on a bar 101, the ends of which bar 101 are pivoted 45 respectively to arms 96 and 98, the latter being provided with an offset arm 102 from which a rod 103 leads to an arm 104 carried by a shaft 105 rotatably mounted in the frame of the apparatus and provided 50 with a suitable knob 106 by which it may be turned.

The operation of my apparatus may be explained as follows.

The parts being, for instance, in the position shown in Fig. 5, if it is desired to 55 consult the reverse side of the guide index, the knob 106 may be turned anti-clockwise which will result in turning the leaf 92 90 degrees to the right, reversing the leaf 91 by turning it to the right 180 degrees; and, simultaneously, turning the leaf 90, 90 degrees to the right so that the face of leaf 90 and the reverse side of 91 will be exposed to view.

65 The items on the guide index are pro-

vided with reference symbols, severally corresponding to the series of index numerals or symbols on the scales on the guides 4, 4, which, in turn, are spaced to correspond with the recesses in the rack bars 18, 18; 70 and, when the appropriate index number has been obtained from the guide index, the operator next proceeds to select the placard corresponding to that number, by sliding the handle 6 forward until its latch 9, 75 engages with the latch 30.

The swinging out of the latch 30 by latch 9 before the latter finds the notch in the former, will cause the latch 30, through the rod 32, to draw over the rack bar 31 out of 80 engagement with the rack 35; if it has been in engagement therewith.

The handle 6 is then slid forward or back until its index line, indicated in Fig. 5, by the double headed arrow, registers 85 with the desired index numeral on the guides 4, 4. This results in moving the traveling frame which carries the placards so as to bring the ends of the rod carrying the placard corresponding with the selected 90 index number directly over the grooved arms 80, 80, of the elevating mechanism.

The plunger 7 is then pressed down, throwing the latch 9 over and releasing it from the latch 30, but, simultaneously, 95 causing the latch 9 to push the rack bar 31 into engagement with the rack bar 35, thereby locking the placard carriage against further movement.

The handle 6 is then slid back until the 100 lower end of the plunger 7 engages with the latch 55, thereby connecting the handle to the elevating mechanism.

A forward movement of the handle next 105 pulls forward the cross head 37 with its pulleys 38, 39, 40, and draws on the cable 84, so as to lift the guide blocks 76, 76, causing their arms 80, 80 to receive and raise the ends of the selected rod 26, which, as they pass up between the cams 79, seat themselves 110 in and are gripped by the grooved ends of the arms 77, whereby the placard rod is firmly locked to the elevating mechanism. The continued forward movement of the handle brings forward the cross head 37, 115 compressing the air in the dash pot cylinders 45, 46, and gradually raising the placard to its full height in the apparatus.

When the handle 6 is slid forward to about the limit of its travel, it passes the 120 end of the latch 65, which snaps into the recess 67, thereby preventing the handle from being moved backward again.

When it is desired to lower the placard to its place in the traveling frame, the plunger 125 7 is released from downward pressure and allowed to slide up under the influence of the spring 8, thus freeing the latch 55, and allowing the cross head 37 to be drawn back gradually, under the control of the dash pot 130

cylinders and pistons, by the descending weight of the cross bar 75 and its connections, the pins 78, 78 on the arms 77, 77 being arrested by the cams 79, 79 so as to raise 5 the arms free from the ends of the rods 26, as they are seated in their notches in the traveling carriage. And, as the cross head 37 reaches the limit of its travel, it will engage the end of the rod 66, pulling it back 10 and swinging the latch 65 out of engagement with the recess 67, thus freeing the handle 6 for another cycle of operation.

By means of my improvements I secure a 15 selective information apparatus, wherein a reversible guide index is associated with placard selecting and exhibiting means in such a way that the amount of space on the index available for associative work with the selective mechanism is largely increased, 20 and the index leaves may be turned without trespassing on the space required for the operation of the selecting and exhibiting mechanism. For it will be observed that the portion of the case behind the guide index 25 leaves is not used for the selecting or exhibiting means, which not only permits its use for turning the index leaves, but relieves the apparatus of the weight of much complicated mechanism which it has been the practice 30 to house in that part of the cases of similar apparatus.

Furthermore, the selecting and exhibiting mechanism is simple, and efficient, and its 35 manually operated parts are moved to and fro on a straight line, the plunger element being designed to perform a plurality of operations, so that through the handle the control of the operator is extended over the full cycle of operation of the mechanism.

40 The apparatus is, also, safely locked in its successive positions, so as to avoid the danger of its parts being thrown out of proper relation during their operation; and the danger of injury from sudden shocks and jars either in raising or lowering the placards is avoided by the pneumatic check 45 mechanism.

It will be understood that the embodiment of my improvements may be varied, as 50 by the use of mechanical equivalents and the like, without departing from the scope of my invention as claimed, the form of construction shown in the drawings being used by me as an illustrative type, and not as an 55 exclusive one.

Having thus described my invention, what I claim and desire to secure by Letters Patent of the United States is:—

60 1. In a selective information apparatus, a case, a group of placards therein, and 65 manually operable, slidable and longitudinally reciprocable actuating means for causing the movement of the placards collectively and the separation and exhibition of any one of them independently.

2. In a selective information apparatus, a case, a group of placards therein, and manually operable, slidable and longitudinally reciprocable actuating means, embodying a vertically movable plunger, for causing 70 the movement of the placards collectively and the separation and exhibition of any one of them independently.

3. In a selective information apparatus, a case, a traveling frame provided with connecting means and with frame locking means, a group of placards carried by the frame, and manually operable, actuating means, slidably reciprocable parallel to the line of movement of the traveling frame, 75 and provided with an element for optionally engaging said connecting means to shift the traveling frame or for actuating said locking means.

4. In a selective information apparatus, 80 a case, a traveling frame provided with connecting means and with frame locking means, a group of placards carried by the frame, and manually operable, actuating means, slidably reciprocable parallel to the line of movement of the traveling frame, 85 and provided with an element for optionally engaging said connecting means to shift the traveling frame or for actuating said locking means and releasing said connecting 90 means.

5. In a selective information apparatus, a case, a traveling frame provided with connecting means and with frame locking means interrelated therewith, a group of 100 placards carried by the frame, and manually operable, actuating means, slidably reciprocable parallel to the line of movement of the traveling frame, and provided with an element for optionally engaging said connecting means to shift the traveling frame 105 or for actuating said locking means.

6. In a selective information apparatus, a case, a traveling frame provided with connecting means and with frame locking means, a group of placards carried by the frame, and manually operable, actuating means, slidably reciprocable parallel to the line of movement of the traveling frame, 110 and provided with elements including a relatively reciprocable plunger, for optionally engaging said connecting means to shift the traveling frame or for actuating said locking means.

7. In a selective information apparatus, 115 a case, a traveling frame provided with connecting means and with frame locking means, a group of placards carried by the frame, and manually operable, actuating means, slidably reciprocable parallel to the line of movement of the traveling frame, 120 and provided with elements including a relatively reciprocable plunger and a pivoted latch actuated thereby for optionally 125 engaging said connecting means to shift the 130

traveling frame or for actuating said locking means.

8. In a selective information apparatus, a case, a traveling frame provided with connecting means and with frame locking means, a group of placards carried by the frame, and manually operable, actuating means, slidably reciprocable parallel to the line of movement of the traveling frame, and provided with elements, including a relatively reciprocable plunger, for optionally engaging said connecting means or for actuating said locking means and releasing said connecting means.

15 9. In a selective information apparatus, a case, a group of placards therein, placard group carrying means, placard engaging and elevating means, and manually operable, actuating means, slidably reciprocable parallel to the line of movement of the placard group carrying means, and for causing the movement of the placard group carrying means and for actuating the placard engaging and elevating means.

25 10. In a selective information apparatus, a case, a group of placards therein, placard group carrying means, placard engaging and elevating means, and manually operable, relatively actuating means, slidably reciprocable parallel to the line of movement of the placard group carrying means, and embodying a reciprocable plunger, for causing the movement of the placard group carrying means and for actuating the placard engaging and elevating means.

40 11. In a selective information apparatus, a case, a group of placards therein, placard group carrying means provided with connecting means and with means for locking the carrying means, placard engaging and elevating means, means adapted to engage with the connecting means, and manually operable actuating means, slidably reciprocable parallel to the line of movement of the placard group carrying means, and provided with an element for engaging the elevating means and for actuating the means adapted to engage with the connecting means and, optionally, to actuate said locking means.

50 12. In a selective information apparatus, a case, a group of placards therein, placard group carrying means provided with connecting means and with means for locking the carrying means, placard engaging and elevating means, means adapted to engage with the connecting means, and manually operable actuating means, slidably reciprocable parallel to the line of movement of the placard group carrying means, and provided with a plunger for engaging the elevating means and for actuating the means adapted to engage with the connecting means and, optionally, to actuate said locking means.

13. In a selective information apparatus, a case, a group of placards therein, placard group carrying means provided with connecting means and with means for locking the carrying means, placard engaging and elevating means, a pivoted member adapted to engage with the connecting means, and manually operable actuating means, slidably reciprocable parallel to the line of movement of the placard group carrying means, and provided with a plunger for engaging the elevating means and for actuating the pivoted member adapted to engage with the connecting means and, optionally, to actuate said locking means.

14. In a selective information apparatus, a case, a group of placards therein, placard group carrying means provided with connecting means and with means for locking the carrying means, placard engaging and elevating means, means adapted to engage with the connecting means, pneumatic checking means, and manually operable actuating means, slidably reciprocable parallel to the line of movement of the placard group carrying means, and provided with an element for engaging the elevating means and for actuating the means adapted to engage with the connecting means and, optionally, to actuate said locking means.

15 15. In a selective information apparatus, a case, a group of placards therein, placard group carrying means provided with connecting means and with means for locking the carrying means, placard engaging and elevating means, means adapted to engage with the connecting means, pneumatic checking means embodying a dash pot and cylinder, and manually operable actuating means, slidably reciprocable parallel to the line of movement of the placard group carrying means, and provided with an element for engaging the elevating means and for actuating the means adapted to engage with the connecting means and, optionally, to actuate said locking means.

16. In a selective information apparatus, a case, a group of placards therein, placard group carrying means provided with connecting means and with means for locking the carrying means, placard engaging and elevating means, means adapted to engage with the connecting means, pneumatic checking means embodying a pair of dash pots and cylinders, and manually operable actuating means, slidably reciprocable parallel to the line of movement of the placard group carrying means, and provided with an element for engaging the elevating means and for actuating the means adapted to engage with the connecting means and, optionally, to actuate said locking means.

17. In a selective information apparatus, a case, a group of placards therein, placard group carrying means provided with con-

necting means and with means for locking the carrying means, placard engaging and elevating means, means adapted to engage with the connecting means, pneumatic checking means embodying a pair of pivoted dash pots and cylinders, tubular means connecting the dash pots, and manually operable actuating means, slidably reciprocable parallel to the line of movement of the placard

5 10 group carrying means, and provided with an element for engaging the elevating means and for actuating the means adapted to engage with the connecting means and, optionally, to actuate said locking means.

15 18. In a selective information apparatus, a case, a group of placards therein, placard group carrying means, actuating means manually operable in a straight line, parallel to the line of movement of the carrying

20 means, to actuate the carrying means, vertically movable placard engaging means, and means, including a flexible element, interposed between the manually operable means and the placard engaging means, to convert horizontal movement of the former into vertical movement of the latter.

25 19. In a selective information apparatus, a case, a group of placards, therein, placard group carrying means, actuating means manually operable in a straight line, parallel to the line of movement of the carrying means, to actuate the carrying means, vertically movable placard-lifting means and gripping means, and means, including a flexible element, interposed between the manually operable means and the placard engaging means, to convert horizontal movement of the former into vertical movement of the latter.

30 40 20. In a selective information apparatus, a case, a group of placards therein, placard group carrying means, actuating means manually operable in a straight line, parallel to the line of movement of the carrying means, to actuate the carrying means, vertically movable, placard-engaging means, and means, including a flexible element connected with said gripping means, interposed between the manually operable means and the placard engaging means, to convert horizontal movement of the former into vertical movement of the latter.

45 55 21. In a selective information apparatus, a case, a group of placards, placard group carrying means, means to shift the carrying means, vertically movable placard-lifting means and gripping means embodying a pivoted lever, and means, including a flexible element, interposed between said shifting means and said pivoted lever, and connected to the lever for causing the lever to grip the placard.

60 65 22. In a selective information apparatus, a case, a group of placards, placard group carrying means, means to shift the carrying

means, a pair of vertically movable placard-lifting means and a pair of gripping means each embodying a pivoted lever, and each cooperating with one of the lifting means, and means, including a flexible element, interposed between said shifting means and said pivoted lever, and connected to the lever for causing the lever to grip the placard.

70 23. In a selective information apparatus, a case, a group of placards, placard group carrying means, means to shift the carrying means, vertically movable placard-lifting means and gripping means embodying a pivoted lever, means including a flexible element, interposed between said shifting means and said pivoted lever, and connected to the lever for causing the lever to grip the placard, and adjustable take up means for said flexible element.

75 24. In a selective information apparatus, a case, a group of placards, placard group carrying means, placard lifting means, manually operable, unitary actuating means for controlling and actuating said carrying means and the lifting means, and a plurality of interrelated pneumatic checking means.

80 25. In a selective information apparatus, a case, a group of placards, placard group carrying means, placard-lifting means, manually operable, unitary, actuating means for controlling and actuating said carrying means and the lifting means, and means for holding said unitary means locked during the return movement of the elevating means.

85 26. In a selective information apparatus, a case, a group of placards, placard group carrying means, placard-lifting means, manually operable, unitary, actuating means for controlling and actuating said carrying means and the lifting means, means for holding said unitary means locked during the return movement of the elevating means, and means, actuated by the elevating means, for releasing said locking means.

90 27. In a selective information apparatus, a case, a group of placards, placard group carrying means, placard-lifting means, manually operable, unitary, actuating means for controlling and actuating said carrying means and the lifting means, and means, including a pivoted latch, for holding said unitary means locked during the return movement of the elevating means.

95 105 110 115 120 125 130 28. In a selective information apparatus, a case, a group of placards therein, placard group carrying means, actuating means manually operable in a horizontal, straight line to actuate the carrying means, vertically movable placard-engaging means, and means, including a plurality of pulleys and a flexible element, interposed between the manually operable means and the placard engaging means, to convert horizontal move-

ment of the former into vertical movement of the latter.

29. In a selective information apparatus, a case, a reciprocable, placard carrying frame provided with side bars having downwardly flaring grooves therein, flat rails beneath said bars, ball bearings interposed between the bars and rails, and means for moving the frame to and fro.

30. In a selective information apparatus, a case, tracks, a reciprocable, placard carrying frame, anti-friction bearings between the tracks and frame, means for causing the travel of the frame relative to the bearings to be less than their travel relative to the tracks, and means for moving the frame to and fro.

LESLIE R. McDONALD.
